UNITED STATES PATENT OFFICE.

PAUL E. GILLESPIE, OF DEARBORN, MICHIGAN.

TOY.

Application filed January 12, 1927. Serial No. 160,707.

My present invention has reference to a wheeled toy and is in the nature of a coaster whereby the operator places one foot on a step or stirrup associated with the improvement and propels the device by stepping on the ground with his other foot until sufficient momentum is imparted to the wheel of the improvement to cause the same to be propelled for a considerable distance.

10 The object of the invention is the provision of a wheeled toy for this purpose that is characterized by simplicity in construction, cheapness in manufacture, ease in operation, and thorough efficiency in use.

15 To the attainment of the above recited objects, the improvement resides in the construction, combination and operative association of parts, a satisfactory embodiment of which is disclosed by the accompanying drawings.

In the drawings:

Figure 1 is a side elevation of a wheeled toy in accordance with this invention.

Figure 2 is a face view thereof.

20 As disclosed by the drawings my improvement contemplates the employment of a yoke member 1 between whose sides there is journaled an axle 2 for a wheel 3. The wheel is preferably rubber tired. One of the arms of the yoke is extended a distance below the other and bent outwardly and

from thence slightly upwardly to provide a step or stirrup 4. The connecting element for the arms of the yoke is in the nature of a socket 5 that receives and has secured therein a handle 6. The handle has fixed thereon an angularly disposed hand grip 7.

35 The user of the toy presses one foot on the step or stirrup and permits his other foot to alternately contact the ground to propel the toy until a desired momentum is obtained, when the user raises his second foot from the ground and is propelled by the toy as long as the wheel thereof freely rotates. 40 In coasting on grades both feet of the operator are raised from the ground and the foot of the operator not occupying the stirrup may be brought into contact with the ground and thus serve as a brake.

45 Having described the invention, I claim:

A wheeled toy including a yoke, a ground wheel having a shaft journaled between the arms of the yoke, one arm of the yoke being projected beyond the other and bent outwardly and slightly upwardly to provide a 50 stirrup, a socket providing the connecting element for the arms of the yoke, a handle received and secured in the socket and a lateral hand grip on the handle.

55 In testimony whereof I affix my signature.

PAUL E. GILLESPIE.
